P. W. DILLON

WIRE FENCE MACHINE DRIVE MECHANISM

Filed Dec. 12, 1923.

FIG. 1

FIG. 2

INVENTOR.
Paul W. Dillon,
BY Walter N. Haskell,
his ATTORNEY.

UNITED STATES PATENT OFFICE.

PAUL W. DILLON, OF STERLING, ILLINOIS, ASSIGNOR TO NORTHWESTERN BARB WIRE COMPANY, OF STERLING, ILLINOIS.

WIRE-FENCE-MACHINE DRIVE MECHANISM.

Application filed December 12, 1923. Serial No. 680,115.

My invention has reference to drive mechanism for wire fence machines, and relates more specially to that class of such machines in which one set of wires is inter-coiled with another set by means of a rotating series of spindles. In these machines one series of wires, comprising the strand wires of the fence, are conducted through the machine in a longitudinal direction, while other wires are introduced transversely of the strand wires, and cut into short sections, the ends of which are twisted upon the strand wires, forming at regular intervals continuous cross-wires, or pickets for the fence. In some cases the cross-wires are not cut into sections, but are attached to the strand wires by short pieces, or tie wires, which are fed into the machine so as to cross the intersection of the strand and cross wires diagonally thereof. In most machines of this kind the spindles are operated in a substantially continuous manner, and at the same rate of speed throughout their movement. At their operating ends said spindles are fitted with projecting pins, which engage the ends of the wires for the purpose of coiling the same, and by reason of the almost continuous rotation of the spindles, such pins frequently interfere with the movement of the wires, catching in the same, and causing breakage of the wires, and injury to the pins.

One of the purposes of the present invention is to provide a drive mechanism the action of which will result in an intermittent movement of the spindles, and which said action is transmitted to the spindles by means of gear mechanism which will impart to the spindles a gradually increasing movement up to a point where the coiling operation is half accomplished, and then gradually reduce as the spindles approach a point of rest. By this means an excessive rate of speed is produced in the spindles in that part of the movement where the greatest speed is required, but which speed is greatly reduced when it is desired to have the spindles come to a stop.

In the drawings:—

Fig. 1 is a plan view of a fragmentary

part of a wire fence machine, equipped with the improvement,

Fig. 2 is a side elevation of the operating devices, and

Fig. 3 is a detail of the gear-wheels 20 and 21, at their greatest movement.

As the improved mechanism does not involve the manner of conducting the wires through the machine, nor of performing the coiling operations by means of which said wires are connected with each other in the formation of a wire fabric, only so much of a machine of usual pattern is shown in the drawings as is deemed necessary for the purposes of illustration, with the parts of the invention adapted and applied thereto. A fragmentary part of a frame is shown, in which 1 and 2 indicate the side-pieces, suitably supported, and united at one point by a cross-plate 3, supporting a series of bearings 4, in which are rotatably mounted the coiling spindles 5, through channels in the centers of which are fed the strand wires 6. Fixed on the rear ends of the spindles 5 are bevel-gear wheels 7, in mesh with similar wheels 8 fixed on a cross-shaft 9, journaled on the frame of the machine, and adapted for rotation by a drive-shaft 10, also rotatably mounted transversely of the frame, by the following means:—

On one end of the shaft 10 is fixed a crank-disk 11, to which is pivoted one end of a pitman 12, the other end of such pitman being loosely connected with an arm 13, rockingly mounted on a shaft 14, also journaled in the frame of the machine, transversely thereof. Fixed on the shaft 14 is a ratchet-disk 15, the teeth of which are capable of successive engagement by a pawl 16, carried by the arm 13. Mounted in the frame is a shaft 19, upon which is rotatably supported a gear pinion 17, in mesh with a gear-wheel 18, fixed on the shaft 14. Each rotation of the shaft 10 results in a rocking movement of the arm 13 forward and back, the length of such movement being sufficient to give to the disk 15 a partial rotation, equalling the space from one of the teeth thereon to the next succeeding tooth. This partial rotation of the disk is imparted to the shaft 14.

and wheel 18, each of such movements of the wheel 18 operating to give a complete rotation to the pinion 17 and shaft 19. The movement of this shaft is imparted to the 5 shaft 9 by means of a pair of eccentrically mounted and odd-shaped gear-wheels 20 and 21, in mesh with each other, and fixed respectively, upon the shafts 19 and 9.

The arrangement of the gear-wheels 20 10 and 21 is such that the small end of the former wheel is in engagement with the end of the other wheel having the greater radius, and the reverse. When the shaft 14 is at rest, the gear-wheels are in the position shown in Fig. 2, and in the initial movement of the shaft 14 and shaft 19, the speed imparted to the gear 21 will be greatly reduced, but as the movement continues, the larger part of the wheel 20 will engage 15 the smaller part of the wheel 21, as a result 20 of which the wheel 21 will gather more speed gradually, until the wheels are in axial alignment, as shown in Fig. 3. From this point the speed will be gradually reduced 25 again, until, just before the shaft 19 comes to a rest, the minimum of speed will be reached once more. As a result the speed 30 of the shaft 9 is accelerated quite rapidly, and correspondingly slowed down after the maximum thereof is reached. This speed 35 variation will also be imparted to the spindles 5, causing them to "pick up" quite rapidly, and as suddenly lose their momentum. This greatly facilitates the operation of the wire coiling devices in machines of this class.

It will be observed that the movement of the shaft 14 is an intermittent one, and that there is a period when such shaft, and all of the parts actuated thereby, are at rest. This 40 period of rest gives ample time for the wire fabric to be advanced so the same will clear

the coiling devices. This is supplemented by the comparatively slow movement of the spindles when they begin to rotate.

What I claim as my invention, and desire 45 to secure by Letters Patent, is:

1. In combination with a wire fence machine and a plurality of wire twisting spindles rotatably mounted therein, a shaft rotatably mounted and operatively connected 50 with said spindles; a drive-shaft in proximity to said first-named shaft; and a pair of eccentric gear-wheels mounted one on each of said shafts, and in mesh with each other, the movement of the gear-wheel on said drive-shaft imparting to the gear-wheel on the other shaft an accelerated speed during a portion of the rotation thereof, and a diminishing speed during the remainder of 55 said rotation, which variations of speed are 60 communicated to said first-named shaft and to said spindles.

2. In combination with a wire fence machine and a plurality of wire twisting spindles rotatably mounted thereon; a shaft rotatably mounted and operatively connected with said spindles; a drive-shaft rotatably mounted in proximity to said first-named shaft; means for imparting to said drive-shaft an intermittent rotation; and a pair 65 of eccentrically shaped gear-wheels, eccentrically mounted, one on each of said shafts, each rotation of the driven gear-wheel imparting to the other gear-wheel a gradually increasing movement during a partial rotation thereof, and a gradually decreasing movement during the remainder of said rotation, said variable movement being communicated to the driven shaft and spindles 70 actuated thereby.

In testimony whereof I affix my signature.

PAUL W. DILLON.
